(57) **CLAIM**

(21) Appl. No.: **29/223,856**

The ornamental design for a test tube retaining and labeling unit, as shown and described.

(22) Filed: **Feb. 22, 2005**

DESCRIPTION

(51) **LOC (8) Cl.** **24-02**

FIG. 1 is a top plan view of a test tube retaining and labeling unit showing my new design. The figure includes on one side a test tube retained longitudinally and on the other side a test tube retained vertically;

(52) **U.S. Cl.** **D24/229**

FIG. 2 is a bottom plan view thereof;

(58) **Field of Classification Search** D24/217-234; D9/755; 206/446, 277; 211/74; 220/519; 422/102, 104

FIG. 3 is a front elevational view thereof;

See application file for complete search history.

FIG. 4 is a rear elevational view thereof;

(56) **References Cited**

FIG. 5 is a front-side cross-sectional view taken along line 5—5 shown in FIG. 1 thereof;

U.S. PATENT DOCUMENTS

FIG. 6 is a left-side cross-sectional view taken along line 6—6 shown in FIG. 3 thereof; and,
